UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

49,849.

Specification for Design.

Patented Nov. 7, 1916.

Application filed August 30, 1916. Serial No. 117,810. Term of patent 3½ years.

To all whom it may concern:

Be it known that I, JOHN S. MONAGHAN, a citizen of the United States, and a resident of the city of Rochester, county of Monroe, and State of New York, have invented a new, original, and ornamental Design for Buttons, of which the following is a specification.

My design is represented in the accompanying drawing, in which;

Figure 1 is a plan view of a button showing my new design. Fig. 2 is a side elevation. Fig. 3 is a section through line 3—3 of Fig. 1.

The button is circular in shape, the edge of which is beveled. The upper face at one side thereof has a circular projection provided with a saucer-shaped cavity. Around the saucer-shaped projection are a series of

circular concentric corrugations, those nearest to the edge of the cavity being complete circles, and those extending toward the outer edges of the cavity being arcs of circles. The bottom surface is provided with a central projection as shown. The upper surface is mottled.

I claim:

The ornamental design for a button substantially as shown and described.

In witness whereof I have hereunto set my hand at Rochester, in the county of Monroe and State of New York, this 25th day of August, 1916.

JOHN S. MONAGHAN.

In presence of—

EARL A. WELLER,
N. D. HULBURT.
